(57) **CLAIM**

The ornamental design for a rattan ball lampshade set, as shown and described.

DESCRIPTION

FIG. 1 is a front, right and top perspective view of the first rattan ball lampshade of the rattan ball lampshade set in FIG. 1.

FIG. 2 is a rear, left and bottom perspective view of the first rattan ball lampshade of the rattan ball lampshade set in FIG. 1.

FIG. 3 is a front elevation view of the first rattan ball lampshade of FIG. 1.

FIG. 4 is a rear elevation view of the first rattan ball lampshade of FIG. 1.

FIG. 5 is a left side elevation view of the first rattan ball lampshade of FIG. 1.

FIG. 6 is a right side elevation view of the first rattan ball lampshade of FIG. 1.

FIG. 7 is a top plan view of the first rattan ball lampshade of FIG. 1.

FIG. 8 is a bottom plan view of the first rattan ball lampshade of FIG. 1.

FIG. 9 is an exploded perspective view of the first rattan ball lampshade of FIG. 1.

FIG. 10 is an enlarged view of detail 10 in FIG. 9.

FIG. 11 is a front, right and top perspective view of the second rattan ball lampshade of the rattan ball lampshade set in FIG. 11.

FIG. 12 is a rear, left and bottom perspective view of the second rattan ball lampshade of the rattan ball lampshade set in FIG. 11.

FIG. 13 is a front elevation view of the second rattan ball lampshade of FIG. 11.

FIG. 14 is a rear elevation view of the second rattan ball lampshade of FIG. 11.

FIG. 15 is a left side elevation view of the second rattan ball lampshade of FIG. 11.

FIG. 16 is a right side elevation view of the second rattan ball lampshade of FIG. 11.

(Continued)

FIG. 17 is a top plan view of the second rattan ball lampshade of FIG. 11.

FIG. 18 is a bottom plan view of the second rattan ball lampshade of FIG. 11.

FIG. 19 is an exploded perspective view of the second rattan ball lampshade of FIG. 11.

FIG. 20 is an enlarged view of detail 20 in FIG. 19; and, FIG. 21 is a front, right and top perspective view of a rattan ball lampshade set showing my design in an environment of use.

The broken lines depict portions of the rattan ball lampshade set that form no part of the claimed design. The broken lines shown in FIG. 21 depict environmental structure which forms no part of the claimed design. The dot-dash broken lines in FIGS. 9, 10, 19 and 20 depict the boundaries of the enlargement and form no part of the claimed design.
